UNITED STATES PATENT OFFICE

95,952

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpo-
ration of New Jersey

Application January 2, 1935, Serial No. 54,663

Term of patent 14 years

To whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic features of the design reside in a plurality of grooves uniformly and regularly spaced from one another and running along substantially straight lines through the entire fabric, the portions between adjacent grooves form-

ing parallel stripes, and series of individual stitches on the face of the fabric at substantially right angles to said grooves and stripes, said stitches being in raised position with respect to said grooves and stripes so as to stand out therefrom.

The dot and dash lines on the drawing define the unit boundaries, the extensions beyond said boundaries indicating its relation to the preceding and succeeding ones.

I claim:

The ornamental design for a textile fabric or similar article of manufacture substantially as shown and described.

JOHN F. GAUL, JR.
